WILLIAM D. JAMES, OF FORT ATKINSON, WISCONSIN, ASSIGNOR TO JAMES MANUFACTURING COMPANY, OF FORT ATKINSON, WISCONSIN, A CORPORATION OF WISCONSIN.

TRACK-SUPPORT FOR LITTER-CARRIERS.

1,250,182.

Specification of Letters Patent. Patented Dec. 18, 1917.

Application filed June 12, 1916. Serial No. 103,072.

To all whom it may concern:

Be it known that I, WILLIAM D. JAMES, a citizen of the United States, residing at the city of Fort Atkinson, county of Jefferson, and State of Wisconsin, have invented new and useful Improvements in Track-Supports for Litter-Carriers, of which the following is a specification.

My invention relates to improvements in track supports for litter carriers, and it pertains more especially, among other things, to that class in which the track is supported from a plurality of pairs of standards which pairs are connected together at their upper ends by one or more transverse arches from which the track is suspended.

Experience has demonstrated that owing to the fact that in assembling the device some of the standards are often set deeper than others, and where the arches have been previously constructed, the track is thereby thrown out of alinement. The standards are set in concrete in nearly all modern structures, and as this is done before the arches are applied, it is impossible to subsequently raise or lower them.

To facilitate setting the arches in proper position irrespective of whether the standards are of the same height, I have provided means whereby the arches may be raised at one end or abutment and supported above the upper end of the standard sufficiently to support the track in its proper position notwithstanding the fact that the standard is set too low. This is of great importance for the reason that the work of constructing the standards and arches is usually done at a distant shop or factory, while the standards are set and arches placed by inexperienced workmen upon the farms where the trucks are used.

My invention is further explained by reference to the accompanying drawings, in which—

Figure 1 represents a pair of track supporting standards connected at their upper ends by clamping sleeves to a transverse arch from which the track is adapted to be suspended.

Fig. 2 is a side view of my device drawn at right angles to that shown in Fig. 1.

Fig. 3 is a detail showing the manner of adjustably connecting the upper end of one

of the standards with one end of one of said transverse arches, and

Fig. 4 is a perspective view of one of the spacing blocks which is adapted to be inserted between the upper end of said standard and the contiguous end of one of the transverse members.

Like parts are identified by the same reference numerals throughout the several views.

The standards 1, support arches 2 from which a track 3 of ordinary construction may be suspended. The lower ends of the standards are embedded in concrete piers 4. The upper ends are connected with the arches by clamping sleeves 5 divided longitudinally and provided with ears 6 through which clamping bolts 7 may pass. The sleeves 5 are adapted to closely fit the standard 1 and the bases of the arches, and they are so constructed that the frictional clamping pressure will be sufficient under ordinary circumstances to support the arch out of contact with the upper end of the standard. But for additional security, I preferably employ spacing blocks 8 which may be made of any desired thickness, or of differing thicknesses and are adapted to be interposed within the clamping sleeve between the abutment or base of the arch and the top of the standard. The clamping sleeves are of sufficient length to securely grip a substantial portion of the standard and also of the arch even though these members may be spaced apart a distance of several inches. The clamping bolts are also so arranged as to secure full clamping pressure upon both the standard and the arch. The spacing members, where used, may be made of less diameter than the standards, no clamping pressure upon them being desired. In practice it is intended to use a number of blocks 8 of different thicknesses, whereby the lower ends of said transverse arch may be adjusted at the desired height throughout its length, without using a large number of spacing blocks at one point. The thick blocks will be used where the arch is to be raised considerably and the thin ones where only a slight elevation is desired.

The track 3 is preferably supported from the transverse arch 2 by a parallel rail 10 and hangers 11, and said hangers 11 are con-

nected at their lower ends to said track 3 and at their upper ends to said rail in any convenient manner. The rail 10 is secured to the arch by metal straps 12. The parts 5 are of ordinary construction and require no further description.

It will be understood that when the track 3 is thus supported in a correct position by the standards 1 and transverse arches 2, the 10 structure will form a convenient and substantial support for vines or other vegetation. The device taken as a whole, including the track, may therefore be not only useful, but ornamental in appearance, whereas 15 it is extremely unsightly when the arches are tilted and the track crooked. In the latter case also the utility of the track is greatly impaired for litter carriers are propelled along these tracks by momentum imparted 20 within the stable and a carrier will not move readily along a crooked track. With my improved construction, metal standards and arches of simple design and great strength may be constructed at a distant shop and 25 symmetrically assembled by inexperienced persons at the place of use, with the standards permanently embedded and rigidly supported in concrete bases or anchors. It has never heretofore been found possible so 30 far as I am aware for farmers to set such posts in concrete and properly attach the arches thereto in such form as to provide a straight track, except in rare instances, where unusual care is exercised in setting the 35 posts.

Having thus described my invention, what I claim as new and desire to secure by Letters Patent, is—

1. In a litter carrier track support, the combination of a pair of standards, an arch having its legs in alinement with the standards, an adjustable securing means for the contiguous ends of the standards and arch legs comprising sectional clamping sleeves each surrounding contiguous ends of the arch and one standard and provided with outwardly projecting opposing clamping flanges on each side, and bolts connecting the flanges of the annulus and adapted to bind the sleeve sections upon the bases of the arch and the standards, the respective sleeves being adapted to coöperate with each other in preventing rotation of the arch members in their respective sleeves. 40

2. In a litter carrier track support, the combination of a pair of standards, an arch connected at its respective ends with said standards, a track connected with said arch, adjusting spacing blocks interposed between the contiguous ends of said standards and arch, clamping members adapted to embrace the opposing ends of said standards and arch, said clamping members being adapted to retain said adjusting blocks in place. 45

In testimony whereof I affix my signature 50 in the presence of two witnesses.

WILLIAM D. JAMES.
